ERNEST J. MARTENS, OF ST. LOUIS, MISSOURI

PLAIT HEADING

Application filed December 2, 1931. Serial No. 578,605.

This invention relates to the provision of certain new and useful means for enabling a curtain to be rapidly and accurately plaited.

The invention has for its general object the provision of novel means to be secured along the top of the curtain at the inner or rear side thereof, and which may be manipulated to enable plaits to be readily formed in the curtain and spaced at equi-distant intervals throughout the width of the curtain.

Another object of the invention is to provide novel means for plaiting a curtain constructed of washable material which is permanently attached to the curtain, so that the curtain may be removed from its support and cleaned and my improved plaiter be capable of manipulation to plait the curtain for re-hanging.

In one form of my invention I provide for plaiting curtains made of heavy fabric, and this form of the invention embodies means to be manually operated for simultaneously forming plaits at intervals throughout the width of the curtain.

In other form of the invention, I provide a construction for use on curtains of light material, such, for example, as lace or net curtains, and in this form of the invention the plaiting is effected by hand, but the invention enabling the operator to readily produce various characters of plaiting, that is, single, double, triple, etc., and to locate the plaits at equi-distant intervals throughout the width of the curtain.

With the above object in view, my invention consists, broadly, in providing a plait heading, comprising a strip of flexible material which is adapted to be secured on the inner side of the curtain at its upper end to extend from side to side thereof, and which strip is provided at suitable intervals with vertically-disposed, equally-spaced stiffening ribs, whereby, upon being brought together, the flexible material will cause the parts of the curtain between the ribs to be doubled back upon themselves to form plaits; and I combine with the structure suitable means to be engaged by a gathering hook to hold the stiffening ribs together and thus maintain the plaits in the curtain.

In one form of the invention, the stiffening ribs are provided with unattached portions which form loops and the curtain is plaited by the operator bringing together by hand two, three, or more, of these loops, to form a single, double or triple plait, as the case may be, and then securing the loops, and consequently the stiffening ribs, together by means of a gathering hook passed through the appropriate number of loops.

In another form of the invention, I secure tape to the strip of material to extend from side to side of the curtain, which is secured at opposite side edges through the strip of material at the points of intersection of the tape with the stiffening ribs, the stiffening ribs have an unattached portion extending over the tape, and in the pocket formed by the tape I insert a pull-tape and secure one end thereof to one end of the strip of material, so that by drawing the pull-tape the stiffening ribs, which in this form are arranged in equally spaced groups, will be brought together to form the plaits as before, and the portions of the tape between the stiffening ribs will be doubled back upon itself to form loops, which loops are then secured together by a gathering hook, to maintain the plaits in the curtain.

The invention is illustrated in the accompanying drawings, in which:—

Figure 1 is a front view, and Figure 2 a rear view, showing the curtain plaited according to one form of the invention;

Figure 3 is a view on an enlarged scale showing the inner side of a portion of my improved plait heading in a flat condition, certain parts being broken away to better illustrate the construction;

Figure 4 is a view similar to Figure 3, but showing the appearance of the plait heading after the pull-tape has been drawn to bring the stiffening ribs together;

Figure 5 is a section on the line 5—5 of Figure 3;

Figure 6 is a diagrammatic view on a reduced scale, showing the manner of spacing the stiffening ribs on the strip forming the foundation, or base, of the plait heading;

Figure 7 is a view of a hook used at the ends of the plait heading;

Figure 8 is a view of one of the hooks for securing together the loops of tape at each plait;

Figure 9 is a plan view of a modified construction of plait heading for use on light weight curtains, the plait heading being shown flat; and

Figure 10 is a view of the plait heading shown in Figure 9, the device however being shown in sections to illustrate the manner of forming a single, double and triple plait, respectively.

Referring now to the drawings, the numeral 1, Figures 2 and 3, illustrates a strip of suitable material, such as crinoline, which forms the base, of my plait heading. At intervals throughout the length of this strip I provide groups of stiffening ribs, as indicated by the numerals 2 in Figure 6. Each stiffening rib is preferably formed by a linen cord secured to the material 1 to extend from top to bottom thereof, although the stiffening rib could be otherwise formed as by being woven into the material of the strip during the process of manufacture. As shown by Figure 6, the stiffening ribs 3 of each group are equi-distant from each other, and the groups 2 of stiffening ribs are equally spaced from each other.

30 In the form of the invention illustrated in the first six figures of the drawings, I provide for plaiting a curtain of heavy fabric, such as velvet, or the like, and to this end I provide means for enabling my device to be readily manipulated to form the plaits.

This construction is illustrated in Figures 3 and 4 of the drawings, in which the numeral 4 indicates a relatively narrow strip of material which is secured at its opposite edges 40 to the material 1 to extend from end to end of the latter and substantially centrally thereof. This strip of material so secured forms a pocket 5, in which I insert, throughout the length of the pocket, sections of hair 45 cloth, or other stiffening material 6, a section of hair cloth being positioned to extend between each two adjacent stiffening ribs and two other sections of stiffening material extending from each end of the material 1 to the adjacent stiffening rib 3. I next secure 50 on the strip of material 4 a length of tape 7, said tape being secured along its opposite side edges from each end of the strip 1 to the adjacent stiffening rib 3, and being un-

55 attached between the stiffening ribs, providing sections, indicated by 7a which are free, in the manipulation of the plait heading as hereinafter described, to be doubled back upon themselves to form loops 7b. The 60 tape 7, secured as described, forms a pocket 8, in which I insert a pull-tape 9, and secure one end thereof to the strip of material 1 at or near the remote end of the latter, as indicated at 10.

65 In applying my improved plait heading to

a curtain, it is secured to the curtain on its inner side and at its upper end, as indicated in Figure 2, and to plait the curtain the operator draws upon the pull-tape 9. This results in drawing the stiffening ribs 3 of the various groups of stiffening ribs together, as illustrated in Figure 4, which operation causes the strips of material 1 between each two adjacent stiffening ribs to bend outward in the manner indicated at 11 in Figure 4, which result is produced by bending the relatively stiff, but flexible hair cloth sections 6, one of which is located between each two adjacent stiffening ribs, and as the material 1 is secured to the rear side of the curtain, the curtain itself will be correspondingly bent outward to form plaits. According to the number of stiffening ribs employed in each group, one, two or three plaits will be formed in the curtain by each group of stiffening ribs. On the opposite side of the strip of material 1, the sections 7a of tape 7 will also be doubled back upon themselves to form one, two or three loops 7b, according to the number of ribs employed, and these loops will then be secured together by means of a suitable gathering hook, illustrated in Figure 8, and indicated by the numeral 12. This hook is provided with a hooked end 13 which is adapted to be passed through an eyelet in a curtain ring, to support the curtain in the usual manner. In Figure 1, I have shown the appearance of the front of the curtain after the same has been plaited in the manner above described, and in Figure 2, I have shown the appearance of the rear side of the curtain and plait heading after the latter has been manipulated to plait the curtain, and after the loops 7b of each group of stiffening ribs have been secured together by a gathering hook 12.

The curtains are not plaited at the immediate side edges thereof, as indicated in Figures 1 and 2, so that the material of the curtain, in the space between the last plait at each side and the edge of the curtain, is left plain, or flat. A corresponding space 14, Figs. 3 and 4, is left on the plait heading, and near the ends of the strip 1. I provide two loops or eyelets 15, in vertical alignment, for the reception of a supporting hook 16, Figure 115 7, which has a prong, 17, for engagement in the eyelets and a hooked end, 18, for insertion in the eyelets of the rings supporting the curtain.

Referring now to Figures 9 and 10, in which I show the form of plait heading I employ for lightweight curtain fabrics and nets, the numeral 19 indicates a strip of material, of crinoline, or the like, secured on which, by stitches extending along its side edges, is a length of tape, 20, which extends from end to end of strip 19. Secured on, or woven in, the strip of material 19 are a series of stiffening ribs, 21, which are vertically-disposed and arranged at equi-distant intervals from

5 a point adjacent one end of strip 19 to a point removed the same distance from its opposite end. As in the device previously described, the stiffening ribs 21 may be in the form of pieces of linen cord secured to one side of the strip 19. These stiffening ribs extend over the tape 20, as indicated at 22, and these portions of the stiffening ribs are free, or unattached, and have a slight fullness, so as 10 to project slightly beyond the face of the tape 20.

15 It will be observed that this arrangement differs from that of the construction first described, for use with heavy curtains, in that the stiffening ribs 21 are equally spaced throughout. This enables the operator to form at will plaits of any desired character, that is, single, double or triple, by bringing together two, three or four of the loops 22 of 20 the stiffening ribs and inserting a gathering hook, 23, through them, as clearly illustrated in Figure 10. As in the previous construction, eyelets 24 are provided at the ends of strip 19 for receiving the end hooks 16, Figure 7.

25 In this construction, the tape 20 merely serves as a re-inforcing or stiffening member.

30 In both forms of the invention, all of the material entering in to the plait heading is formed of washable material, or material that may be cleaned by the process employed in cleaning the curtain, so that after the curtain has been cleaned it may be readily re-plaited and hung.

35 I claim:

1. A plait heading comprising a strip of material adapted to be secured at the top of a curtain to extend from side to side thereof and provided throughout a portion of its 40 length with equally-spaced, vertically-disposed stiffening ribs, each of said ribs having an unattached portion intermediate its ends, said unattached portions being in alignment and forming loops for engagement by 45 a gathering hook.

2. A plait heading comprising a strip of material adapted to be secured at the top of a curtain to extend from side to side thereof, a length of tape secured at its edges to said 50 strip and extending from end to end thereof and a series of equally-spaced, vertically-disposed stiffening ribs mounted on said strip, each of which has unattached portions extending from side to side of said tape to provide loops for engagement by a gathering hook.

3. A plait heading comprising a strip of reinforced material adapted to be secured 55 at the top of a curtain to extend from side to side thereof and provided throughout a portion of its length with equally-spaced, vertically-disposed stiffening ribs, each of said ribs having an unattached portion intermediate its ends, said unattached portions

being in alignment and forming loops for engagement by a gathering hook.

4. A plait heading comprising a strip of material adapted to be secured at the top of a curtain to extend from side to side thereof, 70 a length of tape secured at its edges on one side of said strip of material to extend throughout the length thereof and forming a pocket, a series of groups of equally-spaced, 75 vertically-disposed stiffening ribs provided throughout a portion of the length of said strip, each of said ribs having an unattached portion extending over said tape and providing a loop, and a pull-tape inserted in said pocket and secured at one end to one end of said strip of material.

5. A plait heading comprising a strip of material secured at the top of a curtain to extend from side to side thereof and provided throughout a portion of its length with 80 equally-spaced, vertically disposed stiffening ribs, each of said ribs having an unattached portion intermediate its ends, said unattached portion being in alignment and forming loops, a desired number of said loops being 85 brought together to cause the portions of the curtain and strip between said ribs to be doubled back upon themselves to form plaits, and a gathering hook secured in said assembled loops.

6. A plait heading comprising a strip of material adapted to be secured at the top of a curtain to extend from side to side thereof and provided throughout a portion of its length with groups of equally-spaced, 90 vertically-disposed stiffening ribs, each of said ribs having an unattached portion intermediate its ends, said unattached portions being in alignment and forming loops, means for drawing one end of said strip toward 95 the other to cause said stiffening ribs to be brought together and thereby bend the material between the strips into the form of plaits, and a gathering hook engaging the assembled loops of the ribs forming each 100 105 110

7. A plait heading comprising a strip of material adapted to be secured at the top of a curtain to extend from side to side thereof and provided throughout its length with a 115 number of groups of stiffening ribs, equally-spaced and vertically-disposed, a length of tape secured at its edges to said strip of material to extend from end to end thereof and forming a pocket, each of said stiffening ribs having an unattached portion extending over said tape and forming a loop, a pull-tape inserted in said pocket and secured at one end to said strip of material, whereby upon pulling on the other end of said pull-tape, the stiffening ribs of each group will be drawn together and the material between the adjacent stiffening ribs will be doubled back upon itself to form plaits, and a gathering hook secured in the loops of each group 120 125 130

of stiffening ribs brought together by pulling on said pull-tape.

8. A plait heading comprising a strip of material adapted to be secured at the top of a curtain to extend from side to side thereof and provided throughout its length with a series of groups of stiffening ribs, equally-spaced and vertically-disposed, each of said ribs having an unattached portion intermediate its ends, said unattached portions being in alignment, a length of tape extending from end to end of said strip of material and being secured thereto at its opposite sides at the points of intersection of said tape with said stiffening ribs, said tape forming a continuous pocket and providing unattached portions between each two adjacent stiffening ribs, a pull-tape inserted in said pocket and secured at one end to an end of said strip 15 of material, whereby upon pulling on said pull-tape the stiffening ribs of the various groups will be brought together to cause the interposed material to be doubled back upon itself to form plaits at one side of the strip 20 of material, and the interposed tape to be doubled back upon itself to form loops on the other side, and a gathering hook applied to the loops of each group of stiffening ribs to maintain the plaited condition of the curtain. 25

9. A plait heading comprising a strip of material adapted to be secured at the top of a curtain to extend from side to side thereof, a narrower strip of material secured at its edges to said first named strip to extend from end to end thereof and forming a pocket, pieces of flexible stiffening material inserted in said pocket in endwise relation and extending throughout the length of said strip, a length of tape extending along said second strip of material and forming a pocket, a pull-tape inserted in said pocket and secured at one end to an end of said strip of material, a series of groups of vertically-disposed, equally spaced stiffening cords secured to said strip of material at intervals throughout its length, each of said cords having an unattached portion extending over said tape, and said tape being secured in position at its opposite side edges at the points of intersection with said stiffening cords, to leave an unattached portion of tape between each two adjacent stiffening ribs of the group, whereby when said pull-tape is drawn, the stiffening cords in the various groups will be brought together and thereby cause the interposed material between the ribs to be doubled back upon itself to form plaits at one side of the strip, and the interposed tape to be doubled back upon itself to form loops on the other side of the strip, and a gathering hook securing the loops of each group of stiffening ribs together to maintain the plaits in the curtain. 60

- 65 10. A plait heading comprising a strip of

material adapted to be secured at the top of the curtain to extend from side to side thereof and provided throughout a portion of its length with equally-spaced, vertically-disposed stiffening ribs, and means for holding 70 a series of groups of said stiffening ribs together, at equally spaced intervals throughout the width of the curtain whereby the material of the curtain between the ribs in each group will be doubled back upon itself to 75 form plaits and be maintained in such condition by holding the stiffening ribs together.

In testimony whereof, I have hereunto set my hand.
